UNITED STATES PATENT OFFICE.

WALTER A. NIVLING, OF BOSTON, MASSACHUSETTS.

APPARATUS FOR SIZING YARNS.

1,153,244.

Specification of Letters Patent. Patented Sept. 14, 1915.

Application filed March 7, 1913. Serial No. 752,722.

To all whom it may concern:

Be it known that I, WALTER A. NIVLING, a citizen of the United States, residing at Boston, in the county of Suffolk and State of Massachusetts, have invented a new and useful Apparatus for Sizing Yarns, of which the following is a specification.

By way of explanation it may be stated that in the manufacture of cotton cloth, a sizing of the thread or yarn is necessary, in order to lay the fibers and to strengthen the yarn sufficiently to better fit it for the weaving operation. It is the usual practice to draw or run into the size box, a quantity of the sizing material sufficient to bring about the desired depth and to secure a maximum sizing efficiency; and to restore this depth by an addition of sizing material, when it is noted that there is not sufficient material present in the size box to size the yarn properly. As a result of the foregoing operation, a maximum depth of sizing material and the conditions which promote a maximum efficiency, prevail for an instant only, and at times, work wholly unsuited for the operation of weaving, results, due to the failure to restore a proper depth of the sizing material soon enough, and due to the fact that the depth of the sizing material is constantly changing, and may fall too low. The amount of sizing material taken up by the yarn depends on several factors among which may be named, the density of the solution, or mixture, the character of the material used for the sizing, the tension, the twist, the size of the yarn, and the depth of the submergence, as well as the time the yarn is kept submerged, either from the rate of travel or the depth of the sizing material or both. A varying depth of material therefore affects the length of time during which the yarn is able to absorb the sizing material.

One object of the present invention is to provide novel means for maintaining the size at a constant level in the size box.

Another object of the invention is to provide novel means whereby the supply of size is made to flow continuously through the size box, which feature gives a constantly renewed and uniform size.

Another object of the invention is to provide novel means for disposing of the objectionable matter in the size, also saving

much size which would otherwise suffer deterioration and be lost, notably after a prolonged stoppage of the sizing operation.

Another object of the invention is to provide novel means for returning the contents of the size box to a storage tank, and for directing the contents of the size box into a sewer, at will.

Another object of the invention is the saving of that portion of the size remaining in the size box at the noon stopping hour, at the end of the day, or at the completion of a "set", by returning the same promptly to the storage kettle, before it can deteriorate in quality, congeal, or form in soluble lumps or skins.

It is within the scope of the invention to improve generally and to enhance the utility of, devices of that type to which the present invention appertains.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawing, Figure 1 shows the invention in side elevation, parts being broken away and sectioned; Fig. 2 is a transverse section of the size box; Fig. 3 is a perspective showing a modified means for maintaining a constant level of the size in the size box; Fig. 4 is a vertical sectional detail showing a modified form of the invention; Fig. 5 is a longitudinal section of the tubular stopper employed in Fig. 4; Fig. 6 is a transverse section on the line 6—6 of Fig. 5; Fig. 7 is an end elevation showing a modified form of the invention; and Fig. 8 is a perspective depicting that form of the invention which appears in Fig. 7.

In the drawings, the numeral 1 indicates the size box, and, obviously, any number of size boxes may be provided.

The numeral 2 indicates a size preparation kettle which may be jacketed as shown at 3 and provided with a heating coil 4, either or both of these expedients being resorted to. The specific means whereby the kettle 2 is heated, may be varied greatly

without jeopardizing the invention. The materials for making the size are supplied to the kettle 2 in any desired manner.

Journalized for rotation adjacent the kettle 2 is a shaft 6 carrying a beater 7 operating within the kettle 2, the same constituting an agitating device. The form of the beater 7 and its use or omission may be varied as the judgment of the operator may demand. Any suitable mechanism indicated at 8 may be provided for actuating the beater 7 when the beater is used.

The kettle 2 is equipped with an outlet 9 carrying a cut off valve 10. The outlet 9 from the kettle 2 discharges upon a screen 11 held in the mouth of a storage tank 12.

Should it be desired to heat the contents of the storage tank 12, the same may be jacketed or insulated as at 14, although any other suitable means known in the art, such as a coil 14^a, for heating the storage tank may be resorted to.

A return pipe 15 extends beneath all of the size boxes 1, the return pipe 15 opening 25 into the storage tank 12 above the screen 11. A pump 16 is interposed in the pipe 15. The pipe 15 is provided with a branch 17 for each size box 1, the branch 17 entering a depression 18 formed in the bottom of the size box, the depression 18 being of sufficient size to collect the lumpy portions of the size.

Thrust into the upper end of the branch 17 and located within the size box 1 is a tubular stopper 19 which, at its upper end, may terminate in a funnel 20. The upper end of the funnel 20 is spaced from the bottom of the size box 1, and thus, a constant level is maintained in the size box. The numeral 21 indicates a sewer, the same having a branch 22 for each size box 1, and each branch 22 is connected to the branch 17 of the return pipe 15 below the bottom of the size box 1. A cut off valve 23 is located in 45 the branch 22 of the sewer 21 and a cut off valve 24 is located in the branch 17 of the return pipe 15.

Journalized for rotation adjacent one side of the size box 1 is a guide roller 25 near 50 which is located a vertically adjustable immersion roller 26. Adjacent to the immersion roller 26 are located one or more supporting rollers 27, above which are located heavy compression rollers 28 which may be 55 provided with yieldable facings 29, the facings being ordinarily fashioned from blanket material. The box 1 may be jacketed or insulated as at 1^a and may if desired contain a heating coil 1^b, either or both of 60 these features being resorted to. The material to be sized is indicated by the numeral 30 and passes over the guide roller 25 beneath the immersion roller 26 and between the co-acting rollers 28 and 27. Obviously, 65 by adjusting the immersion roller 26 ver-

tically the amount of submergence of the material is determined, provided that the size is maintained at a permanent level, as is done by the operation of the tubular stopper 19.

Suppose that the valves 23 in the branches 22 of the sewer 21 are closed, that the valves 24 in the branches 17 of the return pipe 15 are open, and that the valves 33, located in the branches 32 of a delivery pipe 31 are open, the pipe 31 entering the storage tank 12 and the branches 32 of the pipe 31 discharging into the size boxes 1. Under such circumstances, the operation of the structure is as follows:—The size contained in the storage tank 12 will pass by way of the pipe 31 into the branch 32 and thence into the size box 1, filling the size box to a level determined by the upper end of the stopper 19. Then, the material 30, passing around and between the several rollers, 25, 26, 27 and 28 will be immersed to a fixed extent, a fixed level of the size in the size box being maintained, because the size is continuously supplied through the pipe 31 and the branch 32. The insoluble or undesirable matter in the size will accumulate on the bottom of the box 1 and the excess portions of the size will flow through the stopper 19 and pass by way of the branch 17 into the pipe 15, the pump 16 forcing the size upon the screen 11, and the size passing thence into the tank 12, to repeat the cycle.

Suppose that it is desired to return all of the size in the size box 1 to the tank 12. Then, the tubular stopper 19 is lifted, and all of the size, will pass into the branch 17 and by way of the pipe 15 onto the screen 11 and into the tank 12.

When it is desired to discharge all of the size into the sewer 21, the valves 24 are closed and the valves 23 are opened. Thereupon, when the stopper 19 is lifted all of the size, will flow into the branch 22 and thence into the sewer 21, and the box may be 110 cleansed thoroughly by washing.

A fresh supply of size may be run into the tank 12 at any time, from the kettle 2 by opening the valve 10. The consistency of 115 the size may thus be regulated.

In Fig. 3, a slight modification in the means for maintaining the level of the size constant is shown. This device, it is to be understood, may be used in connection with the return mechanism and delivery mechanism and with the heating and storing structure shown in Fig. 1, the only modification being in the size box connections.

In Fig. 3, the size box is denoted at 34, and a nipple 40 enters one end of the size box 34 in a groove or depression in the bottom of the size box. The outer end of the nipple 40 enters one branch 38 of an inverted, U-shaped pipe 35 which is located outside of the size box. This pipe has a

vent valve 35' whereby the pipe 35 is prevented from acting as a siphon. In the branch 38 below the nipple 40 there is a cut off valve 42. The branch 38 at its lower end discharges into the sewer 44. The other branch 37 of the pipe 35 discharges into the return pipe 43. Communicating with the branch 38 is an angular pipe 39 discharging into the return pipe 43. In the pipe 39 there is a cut off valve 41.

When the valves 41 and 42 are closed, the size will pass through the nipple 40 and then traverse the branches 38 and 37, the size passing into the return pipe 43. The size will be kept at a constant level, determined by the distance of the top of the pipe 35 from the bottom of the size box. By closing the valve 41 and by opening the valve 42, all of the size may be run into the sewer 44. By closing the valve 42 and by opening the valve 41, all of the size may be run into the return pipe 43. The pipe 43 in Fig. 3 corresponds to the pipe 17 in Fig. 1.

When the structure herein disclosed is added to a plant already installed, the preparation kettle may be made to exercise also the function of a storage kettle. There may be several preparation kettles when more than one kind of size is used.

The form shown in Fig. 3 is preferable when the invention is applied to a plant already installed, since by the use of the structure above referred to, a minimum number of changes need be made.

Especial prominence is given to those forms of the invention which appear in Figs. 3, 4 and 8. When these forms of the invention are employed, not only is the surplus size removed, but the objectionable matter which is usually in the form of heavier particles, is removed from the bottom of the size box, the heavier particles obviously tending to gravitate toward the bottom of the size box.

Referring particularly to Figs. 4, 5, and 6, the size box is denoted by the numeral 100 and the tubular stopper by the numeral 101. The stopper 101 is provided in its side and adjacent the bottom of the size box 100 with an opening 102. Located within the stopper 101 is a transverse partition 103, extended entirely across the stopper, the lower end of the partition 103 being prolonged as indicated at 104 into union with

the stopper 101 below the opening 102. A plate 105 is secured to the bottom of the size box, the plate 105 being provided with an upstanding, curved flange 106 which fits closely around the stopper 101.

When the parts are positioned as shown in Fig. 4, the surplus size in the box 100 will pass into the stopper 101 through the opening 102, and rising, pass over the upper edge of the partition 103, the size passing then downwardly out of the stopper.

By rotating the stopper 101 through an angle of approximately 180°, the opening 102 will come oppositely to the flange 106 and be closed thereby. Under such circumstances, the surplus size will overflow into the top of the stopper 101 and will pass downwardly therethrough.

Referring to Figs. 7 and 8, the size box is denoted by the numeral 107. A pipe 108 enters one end of the size box, the inner end of the pipe 108 lying in a groove of the bottom of the size box. The pipe 108 communicates with an upright pipe 109 containing a cut off valve 110, the pipe 109 discharging into a pipe 111 which communicates with a sewer 112. Branched off from the pipe 108 is a horizontal pipe 114, entering a casing 115 provided with a three way valve 116. The ends of a loop shaped pipe 117 enter opposite ends of the casing 115. The pipe 117 is provided at its crown with a vent valve 118. An extension pipe 119 enters the lowermost portion of the loop-shaped pipe 117, the pipe 119 communicating with a return pipe 120. Interposed in the pipe 119 is a casing 121 provided with a three way valve 122. Entering one side of the casing 121 is a depending pipe 123 communicating with a return pipe 124.

In that form of the invention which is shown in Fig. 3, the pipes may become stopped up and that form of the invention which is shown in Figs. 7 and 8 will permit a stopped up pipe to be blown out readily by means of a steam connection united with either of the return pipes 120 or 124.

When the three way valve 116 is manipulated to close the pipe 114 and when the valve 110 is open, the size in the box 107 will pass by way of the pipe 108, the pipe 109 and the pipe 111 into the sewer 112.

When the three way valves 116-122 are disposed as shown in Fig. 7, the valve 110 being closed, the size may be drawn off the bottom of the box and will pass into the pipe 119 and by way of the pipe 119 into the return pipe 120. However, by manipulating the three way valve 122, the size may be directed by way of the pipe 123 into the return pipe 124. The size, at the will of the operator, may therefore be returned, either to the heavy size kettle by way of pipe 120 or to the light size kettle by way of pipe 124.

By properly manipulating the three way valve 116, the size will pass through the pipes 108 and 114 to the loop shaped pipe 117, a level being thus maintained in the size box, the size passing from the loop-shaped pipe 117 into the pipe 119 and from the pipe 119 to the return pipe 120 or into the pipe 123 and into the return pipe 124, depending upon the position of the three way valve 121.

It will be understood readily that by prop-

erly manipulating the several valves shown, a stopped up pipe located anywhere in the system, may be blown out by means of a steam connection opening into the pipe 120 5 and 124.

Having thus described the invention, what is claimed is:—

1. In a sizing apparatus, a size box; an outlet for the size box, a portion of the outlet being spaced above the bottom of the box to maintain a constant level in the box, the intake end of the outlet being located close to the bottom of the box to remove the thickened portions of the size simultaneously with the maintenance of a constant level and volume; and means for guiding through the size box the material to be sized.
2. In a sizing apparatus, a size box; means for guiding the material to be sized through the size box, and a combined means for maintaining a constant level in the size box with respect to the guiding means and for draining the box from a point adjacent its bottom.
3. In a sizing apparatus, a size box; means for guiding the material to be sized through

the size box, and a combined means for maintaining a constant level in the size box with respect to the guiding means and for draining the box from a point adjacent its bottom; and means for salvaging the drained material and returning the same to the size box.

4. In a sizing apparatus, a size box; an outlet for the size box, a portion of the outlet being spaced above the bottom of the box to maintain a constant level in the box, the intake end of the outlet being located close to the bottom of the box to remove the thickened portions of the size simultaneously with the maintenance of a constant level and volume; means for guiding through the size box, the material to be sized; and means for securing a continuous renewal of the size in the box.

In testimony that I claim the foregoing as my own, I have hereto affixed my signature in the presence of two witnesses.

WALTER A. NIVLING.
